E. W. FERGUSON

RAIL SECURING DEVICE

Filed Dec. 28, 1926

UNITED STATES PATENT OFFICE.

EDWARD W. FERGUSON, OF OGDENSBURG, NEW YORK.

RAIL-SECURING DEVICE.

Application filed December 28, 1926. Serial No. 157,548.

The present invention relates to a securing device for railroad rails and the like, and aims to provide a novel and improved structure which may be conveniently attached to 5 rails and ties for efficiently holding the rails against spreading and becoming loose during continual traveling of rolling stock thereover.

Another object of the invention is the provision of a tie plate to be positioned between the rail and tie having openings therein through which rail securing spikes may be driven into the tie, said plate having grooves in the upper face thereof for receiving, guiding, and bending prongs carried by the spikes so that when the heads of the spikes engage the upper surfaces of the flanges of the rail, the prongs will extend under said flanges, thus preventing the working of the 20 spikes from the tie.

It is also an object of the invention to provide a rail securing device of the above indicated character, which is simple and substantial in construction, which can be manufactured economically, and which will be thoroughly efficient and practical in use.

With the foregoing and other objects in view, which will be apparent as the description proceeds, the invention resides in the 30 construction and arrangement of parts, as hereinafter described and claimed, it being understood that changes can be made within the scope of what is claimed, without departing from the spirit of the invention.

The invention is illustrated in the accompanying drawing, wherein:

Figure 1 is a vertical cross section through a rail showing my improved securing device attaching the rail to a tie,

Figure 2 is a top plan of the same,

Figure 3 is a vertical cross section through the tie plate,

Figure 4 is a fragmentary vertical section taken on line 4—4 of Figure 2, showing the spike partially driven into the tie before the prongs carried by the spike are bent, and

Figure 5 is a side elevation of one of my improved spikes.

In carrying out the invention, the numeral 50 10 designates a tie having positioned thereon a rail plate 11 upon which is supported a rail 12, said rail extending at right angles to the tie as in the usual manner. The rail plate 11 is of a length greater than the width 55 of the flange of the rail and has provided thereon at each end thereof upstanding lugs

13 which engage the opposite edges of the flange of the rail so as to prevent side movement of the rail with relation to the plate. The lugs 13 at each end of the plate are 60 spaced from each other and said plate is provided with a pair of openings at each end thereof extending therethrough, said openings being designated by the numeral 14. The openings are arranged so that when 65 spikes 15 are extended therethrough and driven into the tie 10, the heads 16 of said spikes will engage over the flange of the rail 12 so as to hold said rail and plate against movement with relation to the tie. 70

In the upper surface of the plate 11 extending longitudinally thereof are two pairs of grooves 17, each pair of grooves extending to opposite sides of spikes arranged at opposite ends of the plates, the inner edges 75 of each pair of grooves being in alignment with the edges of the openings 14 through which the spikes extend. The ends of the grooves 17 are curved, as at 18, so as to present rounding surfaces, the object of 80 which will be set forth as the description proceeds. The spikes 15 have arranged on opposite sides thereof, adjacent the side over which the head 16 extends, integral prongs 19, which are joined to the spike at their upper ends, as at 20. The lower ends of the prongs 19 are curved, as at 21, for providing surfaces for engaging the curved surfaces 18 of the grooves 17 so that when a spike is driven into a tie, the curved ends of the 90 prongs engaging the curved surfaces of the grooves will direct said prongs under the flanges of the rail as said spikes are driven, so that when the heads of the spikes engage the upper surfaces of the flanges, the prongs 95 19 will lie in the grooves 17 beneath the flange. Thus, it can be seen that the spikes are attached to the rails against movement with relation thereto.

In Figure 4 of the drawing, I have illustrated a spike as being partially driven into a tie with the curved surface 21 of a prong 19 engaging the curved surface 18 of a groove, which will illustrate the manner in which the prongs are turned beneath the flanges of the rails during driving of a spike.

The undersurface of the plate 11 is provided with a series of longitudinal grooves 23 for lightening the weight of the plate and for permitting better contact with the tie.

It is to be noted that the grooves 17 are arranged in positions with relation to the

openings 14 through which the spikes are driven, so that the prongs will engage into said grooves during driving of the spikes in order that said prongs will be directed beneath the flange of the rail. As the spikes are substantially square in cross section and the openings 14 in the plate 11 are of substantially the same shape, it can thus be seen that the spikes will not be permitted to turn during the driving thereof, which also aids in properly aligning the prongs with the grooves prior to their entrance thereto.

Having thus described my invention, what I claim as new is:

1. A rail securing device in combination with a rail and tie, comprising a plate arranged between said tie and rail and having openings extending therethrough, spikes adapted to be driven into said tie through said openings in said plate until the heads of said spikes engage over the flange of said rail, and means on said spikes adapted to engage said plate and be turned under said rail during driving of said spikes.

2. A rail securing device in combination with a rail and tie, comprising a plate arranged between said tie and rail and having openings extending therethrough, spikes adapted to be driven into said tie through said openings in said plate until the heads of said spikes engage over the flange of said rail, and prongs carried by said spikes and adapted to engage said plate and be turned under said rail during driving of said spikes.

3. A rail securing device in combination with a rail and tie, comprising a plate arranged between said tie and rail and having openings extending therethrough, spikes adapted to be driven into said tie through said openings in said plate until the heads of said spikes engage over the flange of said rail, and prongs carried by said spikes and adapted to engage said plate and be turned under said rail during driving of said spikes, said prongs having the lower ends thereof beveled so as to guide them under the rail.

4. A rail securing device in combination with a rail and tie, comprising a plate arranged between said tie and rail and having openings extending therethrough, said plate also having grooves arranged adjacent said openings and extending under said rail, spikes adapted to be driven into said tie through said openings in said plate until the heads of said spikes engage over the flange of said rail, and prongs carried by said spikes adapted to engage in said grooves in said plate and be turned under said rail and be received in said grooves upon completely driving said spikes.

5. A rail securing device in combination with a rail and tie, comprising a plate arranged between said tie and rail and having openings extending therethrough, said plate

also having grooves arranged adjacent said openings and extending under said rail, spikes adapted to be driven into said tie through said openings in said plate until the heads of said spikes engage over the flange of said rail, and a pair of prongs carried by each of said spikes on opposite sides thereof and having the lower ends thereof beveled so as to direct said prongs under said rail in said grooves during driving of the spikes.

6. A rail securing device in combination with a rail and tie, comprising a plate arranged between said tie and rail and having openings extending therethrough, said plate also having grooves arranged adjacent said openings and extending under said rail, spikes adapted to be driven into said tie through said openings in said plate until the heads of said spikes engage over the flange of said rail, and prongs arranged on opposite sides of said spikes adjacent the side engaging the flange of the rail and being attached to said spikes at their upper ends, said prongs having the lower ends thereof beveled so as to cause said prongs to be bent under said rail and received in said grooves after completely driving said spikes.

7. A rail securing device in combination with a rail and tie, comprising a plate arranged between said tie and rail and having openings extending therethrough, said plate also having grooves arranged adjacent said openings and extending under said rail, said grooves having the ends thereof curved adjacent said openings, spikes adapted to be driven into said tie through said openings in said plate so that the heads thereof will engage over the flanges of said rail, and prongs carried by said spikes at opposite sides thereof and secured to said spikes at their upper ends, said prongs having the lower ends thereof beveled so as to engage the curved surfaces of said grooves in order to direct said prongs under said rail and be received in said grooves after the spikes have been completely driven.

8. A rail securing device in combination with a rail and tie, comprising a plate arranged between said tie and rail and having openings extending therethrough, upstanding lugs arranged upon said plate for engaging the opposite edges of the base flange of said rail, said lugs being arranged between the openings in said plate and in alignment therewith, spikes adapted to be driven into said tie through the openings in said plate until the heads of said spikes engage over the flanges of said rail, and prongs carried by said spikes and adapted to engage said plate and be turned under said rail during the driving of said spikes.
